(57) **CLAIM**

The ornamental design for an adjustable return eyeball valve for flow synchronization, as shown and described.

DESCRIPTION

FIG. 1 is a perspective view of the front side of my adjustable return eyeball valve for flow synchronization; FIG. 2 is a perspective view of the back side thereof; FIG. 3 is an elevation view of the front side thereof; FIG. 4 is an elevation view of the back side thereof; FIG. 5 is an elevation view of the left side thereof; FIG. 6 is an elevation view of the right side thereof; FIG. 7 is a plan view of the top side thereof; and, FIG. 8 is a plan view of the bottom side thereof. The broken lines shown in the figures are for the purpose of illustrating portions of the adjustable return eyeball valve for flow synchronization and form no part of the claimed design.
